UNITED STATES PATENT OFFICE

2,061,473

KNITTING MACHINE

Harry McAdams, Reading, Pa., assignor to Nolde and Horst Company, Reading, Pa., a corporation

Application January 14, 1932, Serial No. 586,635

17 Claims.

(Cl. 66—36)

This invention relates to improvements in knitting machines.

The primary object of this invention is the provision of an improved knitting machine embodying an improved mechanism for controlling knitting needles in plating operation.

A further object of this invention is the provision of an improved knitting machine upon which plated fabrics can be knitted with a wide variety of reverse plated figures and designs appearing therein.

A further object of this invention is the provision of a knitting machine embodying improved reverse plating pattern controlling mechanism.

15 A further object of this invention is the provision of a knitting machine for the production of plated fabrics, embodying an improved needle controlling jack and jack operating cam construction.

20 A further object of this invention is the provision of an improved jack for knitting machines.

A further object of this invention is the provision of an improved method for the production of reverse plated fabric.

25 A further object of this invention is the provision of an improved plated fabric.

Other objects and advantages of this invention will be apparent during the course of the following detailed description.

30 In the accompanying drawings, forming a part of this specification, and wherein similar reference characters designate corresponding parts throughout the several views.

Figure 1 is a front elevation of the improved 35 knitting machine.

Figure 2 is a fragmentary side elevation of the improved knitting machine.

Figure 3 is a vertical cross sectional view taken 40 through the cylinder of the improved knitting machine showing the association therewith of a series of selectively operated jack actuating cams.

Figure 4 is a view on a developed plane of the 45 needle set and cooperating series of jacks in associated relation with jack and needle operating cams.

Figure 5 is an enlarged fragmentary view of a 50 piece of fabric which may be knitted on the improved machine, showing merely by way of example one design which may be knitted with the machine.

Figure 6 is an enlarged fragmentary view of a 55 pair of knitting needles, one of them positioned for receiving the yarns during normal plating, and the other being positioned for receiving yarns to effect reverse plating.

Figure 7 is a side elevation of an improved jack used upon the machine.

Figure 8 is a fragmentary view showing on a developed plane the pattern control lugs which, thru a lever and cam mechanism, control actuation of the jacks and needles of the machine.

Figure 9 is a fragmentary rear view of the lower portion of the knitting machine, showing more particularly the pattern drum actuating mechanism.

Figure 10 is an enlarged fragmentary cross sectional view through an upper portion of the cylinder, showing the improved construction thereof and association of the needles and jacks therewith.

Figure 11 is a perspective view of a lever mechanism associated with the knitting machine between the pattern control drum and the jack actuating cams.

Figure 12 is a plan view of a cam block of the 20 improved machine.

Figure 13 is a fragmentary vertical sectional view taken through the knitting machine cylinder, showing more particularly the manner in which a cam actuates an auxiliary jack for elevating a 25 predetermined needle or needles of the machine for the taking of additional yarns.

In the drawings, wherein for the purpose of illustration are shown preferred and modified forms of the invention, the letter A may generally designate the improved knitting machine, which may include a frame B; cylinder C; means D to operate the cylinder; a set of needles E; a set of jacks F, and means G to actuate the jacks. By way of example a piece of fabric H has been 30 shown in Figure 5, but it is to be understood that a wide variety of designs and fabrics may be knitted upon the improved machine.

The knitting machine generally partakes of certain characteristics of the Banner type of 40 knitting machine disclosed in U. S. Patent #933,443. The frame B has a supporting bed 20 upon which the cylinder C is rotatably mounted. The means for rotating and oscillating the cylinder C are of any approved type, preferably 45 similar to those shown in the patent above mentioned. The cylinder is driven off a main shaft 21, shown in Figure 9 of the drawings, whereon are positioned the usual pulleys and gearing, including a pinion (not shown) for driving a larger gear 23, shown in Figure 9, known conventionally as the "104" gear, which is suitably mounted upon a shaft 24. The main drive shaft is also 50 provided with the usual quadrant 25 for recipro- 55

cating the cylinder during the knitting of the heel and toe, as is usual.

The needle cylinder C is of a special construction. It is considerably longer than the conventional knitting machine cylinder and is provided with needle grooves 26 therein. At its lower end the cylinder is anchored, as shown at 27 in Figure 3 of the drawings, to the gear 28 which forms a part of the cylinder driving means D, as will be well understood by those skilled in the art. The grooves 26 are relatively deep, since they are intended to receive a plurality of jack and needle elements whose surfaces are suitably cammed to perform operations to be subsequently described.

15 By referring to Figures 3 and 10 of the drawings it will be noted that the upper end of the cylinder C is provided with a reduced annular extension 28' which receives a hardened steel ring 29 thereabouts; the latter being provided with a downwardly facing beveled shoulder 30 overhanging the upper ends of the slots 26 in the cylinder C for the purpose of providing a cam shoulder against which the main jacks 31 of the set of jacks F operate, in order to cam the needles 32 of the set of needles E radially outwardly in the grooves into position for normal plating. It is to be noted that the steel ring 29 is also slotted at 33 providing continuations aligning with the slots 26, wherein the needles 32 are also received.

20 The steel ring 29 is properly held in preferably permanent position by means of a brass cap 35, which includes a skirt extending downwardly into the cylinder, and soldered in place as at 36. This cap 35 is provided with radial grooves 37 therein for slidably receiving the usual sinkers 38; the said cap being finished quite similar to the top of any conventional knitting machine cylinder.

25 The needles 32 of the set of needles E are each of the conventional latch type; half of them having long butts 40 and the remaining having short butts 41. The longer butts 40 are designated in full black in Figure 4 of the drawings.

30 The main jacks 31 each include a stem or body portion 43 which is widest at the lower end and there supports a plurality of frangible butts 44, 45, 46, 47, 48, and 49. Of course, the number of butts provided on the shank may vary, but by way of example the jack 31 is shown as having six frangible butts. Each of these butts may be snapped off at its juncture with the body, or at any place along its length, so that any desired arrangement of butts may be omitted from any individual jack or readily made into a butt of a desired length. At its upper end the jack 43 is reduced inwardly from the edge 50 of the jack which slides against the bottom of the cylinder slot, to provide an upwardly facing sloping shoulder 51 which is adapted to ride against the downwardly facing shoulder 30 at the top of the cylinder C, in order that as the jack is slid upward in its slot the upper end will be moved radially outwardly in the slot for pushing the needle 32 cooperating therewith in a radially outward direction, as will be quite apparent from the positions of the needles shown in Figure 3 of the drawings, and elsewhere. The body 43 of the jack 31 is further reduced at a point below the shoulder 51 but along the opposite edge 52 thereof to provide an upwardly facing sloping shoulder or cam edge 53 against which the lower end of the needle 32 cooperating therewith is adapted to ride, as the jack is slid upwardly in its slot, for urging the lower end of the needle 32 radially outwardly at the same time that the upper end 75 of the needle is being urged radially outwardly

by the riding of the jack shoulder 51 against the cylinder surface 30. This is shown at the upper right hand portion of the cylinder in Figure 3. With such arrangement the needles are bodily moved radially outwardly or transversely to the 5 axis of the cylinder C in contradistinction to a mere rocking or tipping action of the needle which has heretofore been the practice. Auxiliary needle operating jacks 55^a and 55^b, as shown in Figure 4, may be used in a cooperative action 10 with the jacks 31 for pushing certain needles upwardly in order to receive contrasting yarns. The jacks 31 are therefore provided with upwardly facing shoulders 56 along their forward edges just above the topmost of the butts 44, 15 against which the lower edge of the auxiliary jacks may engage. The auxiliary jacks slide in the cylinder slots forwardly of the front edges of the main jacks 31, and have independent cam means for actuation, as will be subsequently described. These auxiliary jacks may have butts 57 thereon of any approved length; both the body of the jacks 55^a and 55^b and the butts being frangible in order that they may be broken off at desired lengths. 20 25

The jack actuating means G preferably includes a supporting block 60 which is provided with a vertical series of slots 61 horizontally arranged therethrough. The block 60 is open at a side to permit the various cams to be assembled therein; the open side being then closed by means of a plate 63, shown in Figure 12 of the drawings. The block 60 is provided with a lateral base extension 64 apertured for receiving suitable bolts by means of which to attach it to the supporting bed 20. Flat, elongated and horizontally positioned cams are slidable in the passageway 61, as shown in Figures 3 and 12 of the drawings. It is of course understood that any desired number of passageways 61 may be provided. In the preferred instance eight of such slots are provided. In the uppermost of them is placed a slidable cam 66, the cam head 67 of which is canted at an angle, and in position for actuation of the auxiliary jacks, as will be subsequently described. In the other passageways 61 of the block G there are disposed similarly formed strip cams 68, 69, 70, 71 and 72, which are adapted for actuation upon the butts of the main jacks 31, located at the various levels thereon. These cams 68 to 72 are similarly formed and at their outer ends are cut away to provide a beveled cam face 73, shown in Figure 12 of the drawings, against which the jack butts ride in order to effect the elevation of the jacks in a selected arrangement. As is shown in Figure 12 of the drawings the cams 66 and 68 to 72 inclusive are normally spring urged into engagement at their cam ends toward cylinder C, and of course in position to actuate the various jack butts which are interposed in their path. Thus, a contractile spring 75 may be provided for each such cam, secured at 76 upon the block at one end, and at 77 upon the outer end of the respective cam. Stop pins 78 may be positioned on the cams for engagement with the block 60 to prevent contact at their cam ends with the cylinder, if desired. 55 60 65

The jack actuating means G further includes a pattern control wheel or drum 79, best shown in Figures 2 and 9 of the drawings, which is rotatably mounted upon the machine frame at 80. This drum 79 supports a plurality of lugs intended to actuate a system of levers for selective control of the various cams mounted in the 75

block 60 and elsewhere. The drum 79 is actuated in a step by step movement off the cylinder driving mechanism of the machine, and preferably in a manner similar to that described in 5 my co-pending application Serial No. 558,798, filed August 22, 1931. Adjacent the frame of the machine it is provided with a rigid ratchet wheel either integral or fixedly attached therewith, designated at 81. This ratchet wheel is 10 provided with sixty teeth about the circumference thereof. Generally, the conventional "104" gear wheel 23 rotates once for every four revolutions of the cylinder C. Since it is intended that the drum 79 be advanced for the length of 15 one tooth for two revolutions of the machine cylinder, the gear wheel 23 is provided with a pair of diametrically opposed pins 82 on a side thereof. As has been set forth in my co-pending application Serial No. 558,798, above mentioned, 20 the pins 82 have rollers thereon which are in position to engage a pivoted lever 83. The lever 83 is keyed upon a shaft 84 mounted upon the frame, as shown in Figure 2. The shaft 84 is also provided with an arm 85 keyed therewith, which 25 intermediate its ends is provided with a pivoted pawl 86. The pawl arm rests by gravity upon the teeth of the ratchet wheel 81. A spring 87 normally draws the lever 85 into a position where the arm 83 will be engaged by the lugs 82 as the 30 wheel 23 rotates. It will be readily understood that engagement of the lugs 82 with the arm 83 will throw the pawl arm 86 rearwardly for advancing the ratchet wheel, and its drum.

It will be necessary during the knitting of some 35 portion of a stocking to prevent rotation of the drum 79. Means is provided, as has been described in my co-pending application Serial No. 558,798 above mentioned, to hold the pawl actuating lever out of the path of movement of the 40 lugs 82. This mechanism includes a bell crank lever 88 pivoted on the frame of the machine, one end of which is in position for abutment against a surface 89 of the arm 85, as shown in Figure 2, in order to hold the lever 83 inoperative. The spring 87 will of course be tensioned 45 under such circumstances. The bell crank lever 88 is provided with a rod 90 pivoted thereto and at its opposite end pivoted to the free end of an arm 91. The latter is mounted upon a shaft 92 on the fore portion of the machine, shown also 50 in Figure 1 of the drawings. The pattern chain 93 is provided with appropriate lugs 94 adapted to operate against an arm 95 pivoted on the front of the machine and in position to act against an arm 96 upon the shaft 92 for rocking the latter 55 in order to trip the bell crank lever 88. The latter is normally held inoperative by means of a bell crank lever 97, which has one end thereof in position to be engaged by suitable pins 98 on the circumference of the drum, as shown in Figures 2 and 9 of the drawings. These pins may be selectively placed on the drum to operate the lever 97 at desired intervals. The other arm portion of the lever 97 is suitably notched in 60 stepped relation to receive a pin 100 which is rigid upon the side of the bell crank lever 88. During step by step advance of the drum 79 the bell crank lever 97 is in the position shown in Figure 2 for engaging the pin 100 and holding the bell crank lever 88 out of operating position 65 upon the arm 85. However, as soon as lug 98 trips the bell crank lever 97 the pin 100 will be released and the spring 101 will throw the bell crank lever 88 into position against the arm 95 in order to hold the arm 83 out of the path 70 75

of travel of the lugs 82, so that the drum cannot be advanced until a lug 94 on the pattern chain actuates the above described mechanism.

As an example of one form of knitted fabric which may be produced upon the improved machine, the fabric H is illustrated in Figure 5 of the drawings. It is formed of a backing or body yarn 110, and a facing or plating yarn 111. The plating yarn of course appears on the face of the fabric and the body yarn is concealed therebeneath. In the example shown the backing yarn is black and the facing yarn is white, although any colored yarns may be used in lieu thereof. It is my intention to produce a figured effect or design by reverse plating the yarns 110 and 111, 15 and within the design and in association therewith place one or more yarns of contrasting color arrangement with respect to the plating and body yarns. In the present machine I interknit these additional yarns of contrasting color by what is known as the floating thread method. For the knitting of the contrasting colored effect within the reverse plated design, in the particular fabric H I use the contrasting colored yarns 112 and 113. Merely by way of example the yarn 112 may 20 be red, and the yarn 113 green in color. While the reverse plated effect may assume any desired shape or formation, it is preferred to knit the same in the fabric H in the form of a closed figure; the floating yarns 112 and 113 being knitted 25 within the closed figure. The reverse plated diamond figure or design appearing in Figure 5 is formed by reverse plating the backing yarn 110 in one of the wales for two successive courses, and then for each pair of successive courses reverse plating the normal backing yarn 110 in the adjacently offset wales. This produces the diamond effect shown in the fabric in Figure 5. Within the diamond design the green yarn 113 is knitted so as to appear on the face of the 40 fabric in those two knitted courses in the fabric which determine the greatest width of the reverse plated diamond design, and in the center wale. In the same courses but in the wales at each side of the center wale the contrastingly colored 45 yarn 112 is knitted so as to appear on the face of the fabric, within the reverse plated diamond design. The yarns 112 and 113 are floated on the inside of the fabric between the various adjacently positioned designs in the fabric, as will 50 be apparent from Figure 5. It will be well understood that many varieties of designs and figured effects may be reverse plated in the fabric, and in a cooperative association with the contrastingly floating yarn or yarns, which may be provided in any desired number. 55

Further referring to the means G, and particularly to the mechanism for operating the various cams upon the block 60 off the lugs of the drum 79, a bell crank lever arrangement is associated with said cams. This arrangement is best shown in Figure 11, and includes a support 114 which may be attached upon the front of the machine frame B. It is provided with a plurality of slots in the front thereof for compactly receiving a plurality of bell crank levers 115, 116, 117, 118, 119, 120, 121, and 122; a pivot pin 123 being provided on the supporting piece 114 for pivoting the said bell crank levers in position. The bell crank levers are provided with upstanding portions which are of various lengths; their upper ends terminating in a stepped relation. The upstanding ends may be laterally offset in a selected arrangement and they are adapted to cooperate against certain laterally extending pins 124 pro- 70 75

vided on each of the cams 66, and 68 to 72 inclusive, between said pins and the machine cylinder, so that upon pulling downward upon the lower ends of the bell crank levers said cams may be moved outwardly away from the cylinder, against the normal spring action. These lower end portions of the bell crank levers are laterally offset to relatively space them, and each of them are provided with a plurality of openings therein whereby to attach a connecting rod any desired place along the length thereof in order to actuate the respective cam for the desired distance.

Drum actuated levers 130 are pivoted at 131 upon the frame of the machine, intermediate their ends. Their forward ends are pivotally connected at 132 with upwardly extending connecting rods 133; the latter being connected, as above mentioned, with the lower outstanding end portions of the bell crank levers 115 to 122 inclusive. It is to be understood that a lever 130 is provided for each bell crank lever, and that the rear ends of the said levers 130 are provided with adjustable lug engaging pieces 135, as shown in Figure 2, which are engaged by the various lugs on the drum 79. Springs 136 normally urge the levers 130 into engagement with the drum 79, as shown in Figure 2. It is readily apparent from the foregoing that when a lug engages the end 135 of a lever 130, the fore end of the latter will be lowered and through the connecting rod 133 a lever will be rocked for actuating its cam.

Referring at this time to the needle and jack arrangement as illustrated in Figure 4, for the knitting of the fabric H illustrated in Figure 5, it will be noted that the reverse plated design is seven needle wales in width, so that seven needles are required in a set to effect the knitting thereof. The needle action is effected through manipulation of the jacks 31. The set of jacks F include a plurality of series of seven jacks each, whereon the butts are arranged to permit of proper cam operation for knitting of the illustrated reverse plated design. Thus, in each of the special seven-jack series there is provided a central jack 31^a with only one long butt 45^a, which corresponds in position to the butt 45 of the jack shown in Figure 7. At each side thereof the jacks 31^b are each provided with only one long butt 46^a, which corresponds in position to the butt 46 of the jack shown in Figure 7. At the remote sides of the jacks 31^b there are provided jacks 31^c, each of which has only one long jack 47^a, corresponding in position to the butt 47 of the jack shown in Figure 7. At the remote sides of the jacks 31^c there are adjacently positioned jacks 31^d, which are the last in each series of seven special jacks. They each have one long butt 48^a corresponding in position to the butt 48 of the jack shown in Figure 7. The lowermost butts 49^a on the jacks 60 are shortened for each jack in each series of seven, for a purpose to be subsequently described. At the same level as the butt 45^a the remaining jacks in each of the series of seven, are provided with shorter butts 45^b.

The jacks on the cylinder intermediate the special series of jacks are preferably each provided with one of the long butts 45 and a long butt 49; the remaining butts of the said intermediate jacks being either shortened or broken off completely, since they do not receive any cam actuation.

Referring to an operating cycle of cam, jack, and needle actuation for the knitting of the reverse plated figure or design, by referring to Figure 4 it will be noted that the needles and

jacks travel on the cylinder in the direction shown by the arrow. Of course a cam travel type of machine may be used if desired, since the principles of the invention are applicable to various types of knitting machines. An elevating cam 140 shown, as to the mounting, in Figures 1 and 2 of the drawings, and as to jack actuation, in Figure 4 of the drawings, is slidably mounted in a suitable mounting block 141 upon the machine. It is actuated by a bell crank 142. The latter is actuated either on the conventional pattern control drum 143, or on the special pattern control drum 79. In the machine shown it is actuated off the drum 143; the latter having a lug thereon actuating a lever 144 pivoted at 145 on the machine and through a connecting rod 146 actuating the bell crank lever 142. The function of the cam 140 is to elevate all of the jacks into operative relation with respect to the cams upon the block 60.

For normal plating upon the knitting machine, that is, where on the fabric the plating yarn 111 appears on the outer face of the fabric, the needles are manipulated by vertical upward movement of the jacks 31 into the radially outwardly displaced position, shown for the needle at the right hand side of Figure 3 of the drawings. To effect reverse plating, that is, in order to throw the backing or body yarn 110 to the outer face of the fabric, as when introducing the design or figure into the fabric, the jack remains in the position shown in the left hand part of the cylinder in Figure 3 of the drawings, so that the needle is radially disposed inwardly of the needles upon which normal plated fabric is being knitted. The relation of the needles for knitting of normal plating and reverse plating are shown in Figure 6 of the drawings, wherein the needle 32^a is the one upon which normal plating is effected, and the needle 32^b upon which reverse plating occurs has its hook set backwardly of the other needle. The manner in which reverse plating and normal plating is effected with such cooperative needle action has been set forth in U. S. Patent #1,680,063 and need not here be described. The mechanism of that patent does not permit of as selective arrangement of reverse plating as with my improved machine, since I am enabled to selectively control the actuation of any desired number of needles on the cylinder in order to reverse plate various figures and designs, as well as stripes.

The cam 140 elevates all of the jacks of the cylinder to a position where the upper ends of the jacks lie just below and short of the cam shoulder 30 (see Figure 10), and in position so that the various cams of the block 60 may be selectively operated in order to control the reverse plating action of those needles which lie in the same slots as the seven special jacks above mentioned. The special pattern control drum 79 is provided with an elevated strip or lug 150 thereon, whereon one of the operating levers 130 operates, in such manner that through one of the connecting rods 133 the bell crank lever 118 will be actuated for partially moving the cam 72 on the block 60 to a position which will permit it to engage the long lower butts 49 of each main jack 31, in order to elevate the jacks with long butts 49 upwardly into the slots of the cylinder, so that their upper ends cam against the shoulder 30 of the cylinder, in order to move the needles 32 radially outward to the 75

position shown in the upper right hand portion of the cylinder of Figure 3 of the drawings. This throws the needles into position for normal plated knitting. The cam 12, however, 5 under such circumstances, is withdrawn sufficiently to miss the short butts on the lower ends of the special series of jacks which control the knitting of the reverse plated design. Such 10 special jacks, if elevated at all, to effect normal plated knitting, must be moved by some of the other cams in the block 60, as will be subsequently described. The cams 140 and 12 of course are positioned to actuate the jacks so long as the machine is in condition for knitting 15 the plated design in the fabric.

As the drum 79 rotates, the pattern controlling lug 151, through a lever 130 and connecting rod 133 actuates the bell crank lever 122 withdrawing the cam 68 fully so that it will completely 20 miss the long butt 45^a of the central jack in the series of seven special jacks. Thus, this central special jack 31^a will not cam out the needle which is in the same slot therewith. The lug 151 is of the same length as the effective length 25 of one of the teeth of the ratchet wheel 81, that is, it is of the same length as the throw distance which the pawl 86 is actuated by a single lug 82 thereagainst. Consequently the cylinder rotates twice while the cam 68 is fully out, 30 and as a result the yarns 110 and 111 are reverse plated for two courses on the special needle 31^a. These reverse plated stitches as thus made are indicated in the design at 152 (see Figure 35 5). Lugs 153, 154, and 155 successively actuate the bell crank levers 121, 120 and 119 for successively withdrawing the jack actuating cams 69, 70, and 71, each for two complete rotations 40 of the cylinder. Withdrawal of the cam 68 permits the special jacks 31^b to remain lowered for effecting reverse plating on the needles associated therewith; this reverse plating being represented in the stitches 157 in the design shown in Figure 5. Withdrawal of the cam 70 45 permits the special jacks 31^c to remain lowered and the needles associated therewith thus reversely plate the yarns for two courses of knitting, designated in the reverse plated stitches 158, shown in Figure 5 of the drawings. Withdrawal of the cam 71 permits the jacks 31^d and 50 needles associated therewith to remain lowered, as is shown in Figure 4 of the drawings, so that the needles associated therewith take the yarns in a reverse plating relation, for reversely plating the yarns in two courses, in the design, 55 designated in the reverse plate stitches 159 shown in the design of Figure 5. The pattern control drum lugs 160, 161, and 162 then successively actuate the bell crank levers 120, 60 121, and 122 for withdrawing the cams 70, 69, and 68 in the order stated. The manner in which the remainder of the reverse plated design is completed will be perfectly apparent from the above description. A lowering cam 163 operates in order to lower all of the jacks before reaching the elevating cam 140. Yarn guide arms 164 and 65 165 are provided to respectively feed the white plating and black backing yarns 111 and 110 respectively onto the needles after the needles have been elevated by the stitch cam 166, as 70 shown in Figure 4 of the drawings.

It is sometimes desirable to provide other and contrasting colored yarns in association with the reverse plated design. To that end the yarns 112

and 113 may be employed in the design in a variety of ways, one of which has been shown in the fabric H of Figure 5. It is of course to be understood that these additional yarns, which are knitted into the fabric, after the float method, 5 are optional, since reverse plated designs alone may be used.

When utilizing additional yarns, such as the contrasting colored yarns 112 and 113, it is intended that they will be visible in the fabric in 10 an associated contrasting relation with the reverse plated yarn of the figure. Generally this is accomplished by camming up certain of the needles associated with the seven special jacks of a series above described, by means of the auxiliary or smaller jacks 55^a and 55^b shown in 15 Figures 4 and 13. In the example shown, wherein for two courses the red yarn 113 is knit in the same wale line as the reverse plated stitches 152, with the green contrasting yarn 113 in the same 20 courses but in the adjacent wale lines as the reverse plated stitches 157, a special short auxiliary jack 55^a is placed in the same needle slot of each of the special jack series above described as the central special jack 31^a. Longer auxiliary 25 jacks 55^b are placed in the same slots with the special jacks 31^b, in each of the special series of jacks above described. These auxiliary jacks 55^a and 55^b are in position in the slots to directly 30 actuate against the lower butts of the needles associated in the slots therewith. The top of the three auxiliary jacks 55^a and 55^b in each series are designated at 55^c in Figure 4. These auxiliary jacks 55^a and 55^b are provided with the long butts 35 57 and after being pushed down in their respective slots by lowering of the needles at the knitting point, the said special auxiliary jacks 55^a and 55^b are in the position shown in Figure 4 as they approach the cam 66. The butt 57 of the auxiliary jack 55^a is in position to ride against 40 the cam 66. Its engagement therewith forces the auxiliary jack 55^a upwardly in its slot and against the needle 32 thereabove. This elevates the needle, and prior to elevation of the remaining needles by the stitch cam 166, a yarn guide 45 finger 170 lowers the green yarn 113 to feed it onto this elevated needle. Of course the yarn guide arm 170 does not lower sufficient to permit this yarn to be fed into any other needle than that elevated by the auxiliary jack 55^a. The 50 butts 57 of the other auxiliary jacks 55^b pass beneath the lower end of the cam 66, since they are at a level to permit such passing. However, they ride into engagement with an elevating cam 171, shown in Figure 4, which elevates them to 55 a level wherefrom they may be further elevated by means of a special cam 172.

The main cam block of the knitting machine includes the usual center raise cam, and the stitch cam 166 above described, and also the 60 other stitch cam 174, as will be well understood by those skilled in the art. Special pick cams 175 and 176 are employed with this cam block, in association with the center raised cam and stitch cams, quite similar to that described in 65 detail in my co-pending application Serial No. 209,254, filed July 29, 1927.

The elevating cam 172 receives the butts 57 of the auxiliary jacks 55^b thereagainst and elevates these auxiliary jacks, one after the other, 70 at a point which enables the needles associated therewith to be elevated above the adjacent needles of the cylinder, after such adjacent needles have been elevated by the stitch cam 166 to their maximum position and then slightly lowered by 75

the first pick cam 175. In other words, the needles controlled by the auxiliary jacks 55^b are elevated between the pick cams 175 and 176, and in association therewith the red spotting or contrasting yarn 112 is fed by the yarn guide arm 178 onto the two needles elevated by the elevation of the auxiliary jacks 55^b. During such reception of the spotting yarn 112 upon the two needles elevated by the auxiliary jacks 55^b, the 10 needle between, which previously has received the yarn 113, is in lowered position with its butt against the top of the center raised cam 173, as is shown in Figure 4 of the drawings, so that the yarn 112 cannot be fed to said needle. The needles after elevated by the auxiliary jacks 55^b are lowered by the pick cam 176 to a position where they may be further lowered by the stitch cam 174, together with all of the other needles. This takes place at the knitting point 180. This lowering of the needles by the stitch cam 174 pushes the auxiliary jacks 55^a and 55^b downwardly in their slots in the cylinder to the level at which they approach the cam 66 as above described.

The above mentioned manipulation of the needles by the auxiliary jacks 55^a and 55^b will cause the yarns 112 and 113 to be knitted in the same two courses in which the reverse plated stitch loops 159 appear. As shown in Figure 5 of the drawings the yarn 113 is visibly displayed in 30 stitch loops 181 in the center of the reverse plated design, and at each side thereof the yarn 112 has stitch loops 182 showing on the face of the fabric within the design. The yarns 112 and 113 are floated at the inside of the stocking or 35 fabric being knitted from one figure to another, as can be understood from Figure 5 of the drawings.

The cam 66 is actuated off the drum 79, a lug 185 being provided thereon for actuating thru the 40 lever mechanism above described the bell crank lever 115 which controls the cam 66. Cam 171, as is shown in Figure 1 of the drawings, is actuated by a bell crank lever 186 off of the pattern control drum 143, thru a connecting lever mechanism 187, 45 although this cam 171 may be operated off the drum 79. The cam 172, as shown in Figure 1 of the drawings, is operated by means of a bell crank lever 188 which is actuated thru the above described system of levers off the drum 79 by engagement of one of the levers 130 with a lug 189 positioned on the drum 79.

Under certain circumstances a figure or pattern is not knitted into the fabric. For instance, in knitting a stocking the pattern is taken out of the 55 high splice and sole. Under these circumstances certain of the series of special main jacks are actuated so as to eliminate the reverse plating effect. To that end such series of special jacks which lie in the grooves with the short butt needles 60 whereon the high splice and sole are knitted are provided with lowermost butts 49^b of a length intermediate the short butt length and the long butt length. They are shown in cross section in Figure 4 of the drawings. A special cam 190, 65 shown in Figures 1 and 4, is employed, operated upon by a bell crank lever 191 which is controlled by a connecting lever mechanism 192 off the pattern control drum 143. At the appropriate time this cam 190 is pushed into position to elevate the 70 special jacks having the lower butts of intermediate length in order to cut out the reverse plated design. This will be apparent from Figure 4 of the drawings.

Under certain circumstances it may be desirable to employ auxiliary jacks at the level of the

75 jacks 55^b having butts of different lengths, so that additional colored yarns may be knitted into the design after the float method. The feeding of yarn to the needles controlled by such auxiliary jacks may be controlled by a cam 193, shown in dotted and dash lines in Figure 4 of the drawings and in full lines in Figure 1 of the drawings, controlled off a bell crank lever 194. This cam 193 is not used in the knitting of the design of fabric H, as will be quite apparent.

10 It is to be distinctly understood that all of the cams actuating upon the main, special, and auxiliary jacks may be actuated directly off the improved pattern control drum 79. Furthermore, the cams in the block 60 may be used in a selected 15 arrangement. In fact two of the cams which ordinarily slide in the second and third passage-ways from the top of the block 60 have not been shown in the drawings, since no cams are needed at this point for the design of fabric illustrated. 20 It is obvious that by the drum lug arrangement and the breaking away of the butts of the main jack in a selected arrangement practically any character of figure or design may be reverse plated 25 in the fabric. The primary use of the improved machine will be for the knitting of reverse plated designs, but additional contrasting yarns may be placed within and in association with any reverse plated design after the float method above described.

30 The individual needles and jacks may be yieldably maintained in their positions in the cylinders by means of the conventional contractile springs 200, shown in Figure 13 and elsewhere.

The usual needle actuating cam set may be provided and need not be further described.

35 The whole set of levers 130 may be put out of operation by means 143^a operated off the drum 143.

The drum 79 and its lugs may be provided with 40 means to prevent the quick detachable connection of the lugs on the drum in any desired position.

45 It can readily be understood that by using one, two, three or four operating lugs on the gear 23 the plating may be similarly effected in one to 45 four consecutive courses in the fabric. Indeed it is possible to effect similar plating through any number of consecutive courses.

Various changes in the steps of the method for producing the improved knitted fabric of this invention, as well as changes in the shape, size, and arrangement of parts may be made to the mechanism for producing the various reverse plated and figured effects and designs, without departing from the spirit of the invention or the scope of the 55 claims.

I claim:

1. In a knitting machine, a needle holder, a series of latch needles slidable in the holder, needle actuating cams, a series of jacks for the 60 needles, means operative upon the jacks for moving the respective needles transverse to the normal needle line for reversing the plating of yarns with respect to the plating effected upon the needles when in the normal needle line, a 65 second series of jacks for the needles, and means operating upon the second series of jacks for vertically moving the respective needles to selectively take additional yarns.

2. In a knitting machine, a slotted needle bed, 70 a set of needles in the slots of said bed, a needle cam set, a series of jacks co-acting individually with the needles, said jacks having a series of frangible butts thereon, a series of cams for the respective butts of said jacks, pattern control- 75

ling means for actuating said last mentioned cams, a second series of jacks for certain individual needles of said set of needles, and pattern controlling cam means for actuating said second series of jacks in order to elevate the needles thereby.

3. In a knitting machine, a slotted needle bed, a set of needles slideable in the slots of said bed, a needle cam set, a series of jacks slideable in the slots of said bed individually in co-acting relation with said needles, whereby to radially move the needles inwardly and outwardly, said jacks having a selected arrangement of frangible butts thereon, a series of cams in position to engage the butts of said jacks for actuating the jacks and consequently moving the needles in a selected sequence, means for feeding body and plating yarns to said needles, pattern controlling means for actuating said series of cams, a second series of jacks slideable in the slots of said needle bed and lying in position below the individual needles, and cam means for actuating said last series of jacks for slidably moving predetermined needles in the slots.

4. In a knitting machine, a slotted needle bed, a set of needles slideable in the slots of said bed, a needle cam set, a series of jacks slideable in the slots of said bed individually in co-acting relation with the needles whereby to radially move the needles inwardly and outwardly, said jacks having a selected arrangement of frangible butts thereon, a series of cams in position to engage the butts of said jacks for actuating the jacks and consequently moving the needles in a selected sequence, means for feeding body and plating yarns to said needles, pattern controlling means for actuating said series of cams, a second series of jacks slideable in the slots of said needle bed and lying in position below the individual needles, cam means for actuating said series of jacks for slidably moving predetermined needles in the slots, and means for feeding additional yarns to such needles as actuated by the second series of jacks.

5. In a circular knitting machine, a series of independent needles, means to feed a plurality of contrasting threads thereto in a plating relation, means to actuate the needles for knitting plated fabric, means to actuate a group of said needles for reverse plating the fabric in selected designs in the fabric, means to feed a plurality of additional and relatively contrasting yarns to the needles, and means to elevate predetermined needles of said group to knit said additional threads in wrap within wrap relation in the same courses and in a complementary contrasting design with the reverse plated design and with said additional threads floated on the inside of the fabric between the designs knitted therewith.

6. In a knitting machine, a series of independent needles, means to feed a plurality of contrasting threads thereto in a plating relation, means to actuate the needles for knitting plated fabric, means to actuate a group of said needles for reverse plating the fabric in a selected boundary closed reverse plated design, means to feed a plurality of additional and contrasting threads, which are also relatively contrasted in color, to selected needles of said group, means to actuate said selected needles to knit said additional threads in a wrap within wrap relation in the same courses and in a complementary contrasting design within the boundaries formed by the reverse plated design and in the same wale lines with the reverse plated stitches, and with the

said additional threads floated on the inside of the fabric between the designs knitted therewith:

7. In a circular knitting machine the combination of a cylinder having slots, needles slideable in the slots, jacks slideable in the slots for each of said needles, cam means associated with the cylinder and jacks and needles to bodily move the needles in a selected arrangement radially inwardly and outwardly in substantial parallelism as the jacks are slid in their slots, said jacks having a series of selectively arranged frangible butts thereon, cam means for engaging said butts to actuate the jacks in a selected arrangement, and means to feed backing and facing yarns to the needles.

8. In a circular knitting machine the combination of a cylinder having slots, needles slideable in the slots, jacks slideable in the slots for each of said needles, cam means associated with the cylinder and jacks and needles to bodily move the needles in a selected arrangement radially inwardly and outwardly in substantial parallelism as the jacks are slid in their slots, said jacks having a series of selectively arranged frangible butts thereon, cam means for engaging said butts to actuate the jacks in a selected arrangement, means to feed backing and facing yarns to the needles, auxiliary jacks in the cylinder slots forwardly of the first mentioned jacks and the respective needles, means for actuating said auxiliary jacks to elevate predetermined needles in advance of the knitting point, and means for feeding additional thread to such predetermined needles as they are elevated.

9. As an article of manufacture a one piece needle actuating jack for knitting machines comprising an elongated body having a series of laterally extending relatively spaced frangible butts at an end thereof at different levels, said jack at its opposite end having a sloping cam shoulder on the opposite edge from that edge from which the jack butts project, the said jack body at a point below said shoulder having an upwardly facing sloping needle engaging cam shoulder at its butt projecting edge.

10. In a circular knitting machine the combination of a cylinder, needles slidably mounted on the cylinder for independent action, a set of jacks individually co-acting with said needles upon the cylinder, cam means for selectively moving said jacks to radially move the needles bodily without tipping or bending, a second set of jacks for independent co-action with said needles, and cam means for selectively actuating the last mentioned set of jacks for selective elevation of said needles.

11. In a circular knitting machine the combination of a cylinder, needles slidably mounted on the cylinder for independent action, a set of jacks individually co-acting with said needles upon the cylinder, cam means for selectively moving said jacks to radially move the needles, a second set of jacks for independent co-action with said needles, cam means for selectively actuating the last mentioned set of jacks for selective elevation of said needles, means to feed lining and plating yarns in knitting relation to the needles, and means to selectively cooperatively feed one or more contrastingly colored yarns to the needles in selected relation as they are elevated by the second mentioned set of jacks.

12. In a knitting machine, a needle holder having slots, needles slideable in the slots, needle actuating cams, individual sliding jacks each being non-flexible transversely to the needle line and

positioned in the slots behind the needles, and means to selectively actuate the jacks in the holder to directionally move the needles bodily forward for plating without bending or tipping.

5 13. In a knitting machine, a needle holder having slots, needles slidably longitudinally in the slots, a jack for each of the needles in the slots back of the respective needles, said needle holder having a cam flange thereon engageable by the 10 jacks so as to move the jacks and needles radially as the jacks are moved longitudinally in their respective slots, means to selectively actuate said jacks in predetermined relation, said last mentioned means including butts on the jacks at different levels with respect to adjacent jacks and a 15 series of cams actuatable at different levels upon said butts, other jacks in the slots of the holder below the needles and forwardly of the first mentioned jacks, and means to elevate the last mentioned jacks for elevating the respective needles thereof.

14. In a circular knitting machine the combination of a cylinder, needles slidably mounted on the cylinder for independent action, a set of jacks individually co-acting with said needles upon the cylinder, cam means for selectively moving said jacks in order to move said needles radially, means for feeding a plurality of yarns to the needles in order to normal plate and reverse plate depending upon the normal or radial moved positions of said needles, a second set of jacks for independent co-action with said needles, cam means for selectively actuating the last mentioned jacks for selective elevation of said needles, and means 35 for selectively feeding one or more other yarns upon the needles in their elevated positions as they are elevated by said last mentioned cam means.

15. As an article of manufacture a one piece needle actuating jack for knitting machines comprising an elongated body having a laterally extending series of frangible butts thereon at different levels, said jack body at a point between 5 the ends thereof having an upwardly facing sloping needle engaging cam shoulder at the same edge thereof as that edge from which the butts project.

16. In a knitting machine, a needle holder having slots, needles slidably in the slots, needle actuating cams, individual jacks mounted in the slots behind the respective needles, means to throw the upper ends of the jacks radially outward as they are moved upwardly in their slots in order to 15 throw the hooked ends of the needles radially outward, and means on the jacks to engage the lower ends of the needles as the jacks are moved upwardly and to simultaneous with the action of the last mentioned means to throw the lower ends 20 of the needles radially outward whereby the needles are bodily moved without bending and without tipping in their respective slots.

17. In a circular knitting machine the combination of a cylinder, needles slidably mounted 25 in the cylinder for independent action, means for feeding a plurality of plating yarns to the needles, means for selective and independent direct movement of the needles to effect normal and reverse plated patterning therein, means for feeding a 30 plurality of needle wrapping yarns to the needles, selective means for elevating the needles independently and selectively to take various wrap yarns in the same courses of knitting to produce in complementary relation to the reverse plated 35 patterned effects wrap within wrap contrasting patterned effects in the same courses.

HARRY McADAMS.
